H. A. Frost,

Table-Leaf Support,

No 12,588,

Patented Mar. 27, 1855.

Fig. 1.

Fig. 2.

UNITED STATES PATENT OFFICE.

HENRY A. FROST, OF WORCESTER, MASSACHUSETTS.

MODE OF SUPPORTING TABLE-LEAVES.

Specification of Letters Patent No. 12,588, dated March 27, 1855.

To all whom it may concern:

Be it known that I, HENRY A. FROST, of Worcester, in the county of Worcester and State of Massachusetts, have invented a new and useful Mode of Operating and Supporting Table-Leaves; and I do hereby declare that the following is a full, clear, and exact description of the construction and operation of the same, reference being had 10 to the annexed drawing, making a part of this specification, in which—

Figure 1 is a perspective view. Fig. 2 plan view of the brace or support separate from the table.

15 A, A, A, is the frame and legs of an ordinary table.

B, B, are the leaves.

C, C, is the swing brace or support which is attached to the leaves by the loops or 20 their equivalent at E, E, which allows the brace, C, to swing freely when the leaves are raised.

D, D, are the shoulder pieces against which the brace, C, rests when the leaves 25 are up.

F, is a small projection by which to operate the brace. g represents the brace when the leaves are down, the operation is as follows, when the leaves are raised the brace C C will swing down to the shoulder piece 30 D, in order to lower the leaves take hold of the leaves F and swing the brace up under the leaves when they are dropped the brace will occupy the space between the leaves and the bed piece of the table, the brace or support may be made of either metal or wood. 35

I do not claim the idea of using a brace to support table leaves as such; but

What I do claim as my invention and desire to secure by Letters Patent is— 40

The application to table leaves of a self-acting swing brace or support which shall operate by its own weight, when the leaves are raised, substantially as set forth.

HENRY A. FROST.
